UNITED STATES PATENT OFFICE.

ALFRED B. SMITH, OF TOPEKA, KANSAS.

ANTISSET FOR HENS.

1,213,964.

Specification of Letters Patent. Patented Jan. 30, 1917.

Application filed June 26, 1916. Serial No. 106,041.

To all whom it may concern:

Be it known that I, ALFRED B. SMITH, a citizen of the United States, residing at Topeka, in the county of Shawnee and State of 5 Kansas, have invented a new and useful Antiset for Hens, of which the following is a specification.

The present invention is a device designed to prevent hens from setting, and it 10 is the object of the invention to provide a novel and improved device of that character, which is simple and inexpensive in construction, easy to apply and remove, and thoroughly practical and efficacious in use.

15 With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

20 25 The invention is illustrated in the accompanying drawing, wherein;

Figure 1 is a perspective view of the device. Fig. 2 is a view of the device as applied to the leg of a hen, and in the position 30 to prevent the hen from setting.

The attachment embodies a sleeve 1, which is preferably composed of two arcuate sections 2 hinged together, as at 3, and adapted to be held in closed position in any suitable 35 manner, such as by the provision of a spring catch 4 at the free edge of one section 2 engageable in an aperture 5 with which the other section 2 is provided adjacent its free edge. The sections 2 can be readily swung 40 apart to apply or remove the sleeve 1, said sleeve being adapted to loosely surround the leg of the hen. The sleeve 1 is provided adjacent its opposite ends with annular series 45 of radial wire prongs 6 having their free ends pointed, and the pointed ends of the

two sets of prongs are curved away from one another, whereby to enhance the efficiency of the device.

In use, the sleeve 1 is applied to the leg of the hen, and said sleeve being loose upon the 50 leg can rotate and move longitudinally upon the leg without interference, so as not to prohibit the movements of the hen, other than the setting movement. Should the hen attempt to set, in which act the legs are 55 brought toward a horizontal position, as seen in Fig. 2, the lowermost prongs 6 will engage the nest, while the uppermost prongs 6 nearest the body will prick the body of the hen, thus preventing her from setting. The 60 curvature of the prongs 6 is of advantage in that it brings the pointed ends of the prongs into effective contact with the body of the hen, and the sleeve 1 can be applied to the leg in reversed positions with the same result.

The device is easily removed and applied, and can be manufactured at a small cost, but is nevertheless thoroughly efficient in use.

70 The device in being applied to the leg of the hen will also divert the hen from the setting habit, since the hen will be distracted by the presence of the device, which she will attempt to remove.

75 Having thus described the invention, what is claimed as new is:

An anti-set for hens embodying a sleeve applicable to the leg of a hen, and a set of radial spurs attached to the sleeve adjacent 80 to each end thereof, the free ends of the spurs of each set being curved away from the spurs of the opposite set.

In testimony that I claim the foregoing as my own, I have hereto affixed my signature 85 in the presence of two witnesses.

ALFRED B. SMITH.
